INSULATING DEVICE FOR ELECTRICAL CONNECTIONS

Charles B. Case, Jr., Trenton, N. J.

Application July 6, 1932, Serial No. 621,104

3 Claims. (Cl. 173—361)

My present invention, in its broad aspect, has to do with improvements in means for insulating the terminals of an electrical connection; and in its more specific application, it has to do with improvements in an insulating device which is separable from, and may be sold and merchandised separately with respect to, a conventional electric connection or fitting, such for instance as a terminal plug or socket.

10 I am well aware that it has heretofore been proposed to provide in what is known as a two-part electric plug, a partitioning and insulating member on one part of the plug for preventing short circuiting of the terminal wires leading into 15 the other part of the plug. However, the main objection to forming a plug element with a partitioning element forming an insulator, is that care must be taken when attaching the terminals in the other plug element to make allowances for 20 the partition when the two plug elements are fitted together to complete the circuit. Furthermore this type of plug is costly to manufacture; more or less intricate; and the retail price of necessity is increased or the profit to the retailer 25 reduced. I am also aware that ordinary fibre, or bakelite insulating pieces are old in the form of flat washers; detachable posts; sleeves, specially formed terminals, and the like.

What I propose to do in my present invention, 30 and have done as both experiments and actual practice have demonstrated; is to provide a simple, detachable, cheap and durable insulating member in the form of a circular, square or otherwise shaped flat washer-like element having 35 formed as part thereof, or integrally therewith, a partitioning insulating piece which is at right-angles to one side thereof. The washer-like element having its insulating and partitioning plate or piece extending from one side thereof may be 40 formed of bakelite, fibre, rubber, or any other suitable insulating material, and it is designed to be manufactured, merchandised, and sold separately from the terminal plug and socket with which it is designed to be used, and assembled in 45 the plug or socket when the circuit is completed by attaching the terminals to the posts of the plug or socket. While I have here spoken of my invention with reference to its use with a two-part electrical plug or socket it may be used with 50 other electrical fittings and I speak for the purpose of making myself specifically clear rather than for purposes of limitation of the adaptation and use of the invention.

My insulating washer may be manufactured 55 and sold at a fraction of a cent in price, and is especially adapted for retailing through five-and-ten cent stores, retail electrical stores and the like. Amateur electricians do not have the facilities or skill ordinarily to solder a plug terminal, and unless care is taken to properly attach an 60 electric wire terminal to the post of a plug, short circuiting is almost sure to occur in time for many reasons. Continuous short circuiting (sometimes accompanied by injury and damage) often takes place with electric irons, toasters, 65 table lamps, poachers, and the like. This is the type of device usually tinkered with by one unskilled with electrical practice. By the use of my invention short circuiting is absolutely prevented and a more fool-proof, practical, and 70 efficient terminal connection is provided.

While in the foregoing I have set forth some of the main purposes and advantages of my invention with reference to its practical application to certain specified types of electric connections; it 75 is manifest that both the form, shape, size, and composition of my insulating washer may be changed without departing from the spirit of the invention, and it may be used with other types of electrical equipment not specifically enumerated. 80

In the drawing wherein a preferred form of my invention is illustrated:—

Figure 1 is a top plan view thereof; 85

Figure 2 is a side elevation;

Figure 3 is a perspective view;

Figure 4 is a view of an electrical plug assembly with my device partly in section;

Figure 5 is a side view of a plug element showing my insulating device in place, and 90

Figure 6 is a top plan view of a plug element with my insulating device shown in place with respect to the terminals thereof.

In the drawing wherein like characters of reference are used to designate like or similar parts throughout the several views thereof:— 95

The numeral (1) designates a flat, circular washer-like element which forms the body of my device. While the same is circular in shape, other forms may be used, and it may be made of bakelite, fibre or any other desired insulating material. Formed as part of the element (1), or integral therewith, is a plate like member (2) which rises at right angles from one side of the member (1) and extends to the edges thereof. While the plate-like member (2) is shown rectangular, its shape may be changed or it may be cut down with a knife or shaped up along its edge to suit particular conditions when applied. The washer-like member (1) and the plate-like member (2) carried by the washer-like member form 100

105

110

the complete unit, and they may be formed of an integral casting or stamping, or permanently attached to each other in any suitable manner.

The washer-like member has formed therein 5 slots (3) which are preferably H-shaped to provide fingers (4) for frictionally engaging the terminals of a plug in the manner which will be hereinafter described.

In order to illustrate the application of my invention to one type of electrical fitting, I have 10 shown in the drawing the male element of a conventional type of two-part electric plug, same being designated (5) and having the usual contact member (6); terminal posts (7); lead in wires 15 (8) to the terminal posts, and screw fastenings (9).

As shown in Figures 4, 5 and 6; the lead in wires (8) are attached to the terminal posts (7) on opposite sides of the plug, adjacent each of 20 the contact members (6); it is these lead in wires that are likely to short circuit unless the connections to the terminal posts (7) are soldered or carefully made by an experienced electrician. In order to prevent short circuiting, my present 25 invention is used and applied after the following manner:—

After the lead in wires have been connected to the terminal posts my insulating device is applied by fitting down the washer-like member over 30 the contact members (6) so that they are received through the slots (3) as shown in views 5 and 6, in which case the plate-like partitioning and insulating member (2) fits down between the 35 respective lead in wires (8) which are thus separated and insulated from each other and the interior of the plug is partitioned and insulated so that there is no possibility of chance contact between the lead in wires, terminals or the like on one side of the plug with those on the other; the position of my plate-like partitioning and insulating member (2) being shown with respect to the parts of a conventional plug in Figure 4.

It is believed that the operation, construction, and advantages of my invention will be clearly 40 apparent from the foregoing, but it is emphasized that interpretation of the scope of my invention should only be conclusive when made in the light of the subjoined claims.

I claim:—

50 1. The combination with substantially any conventional terminal plug for electrical connections of the type having a body portion for the lead-in wires and spaced upstanding terminals; a detachable accessory for use therewith comprising a covering member of insulating material adapted to fit over the open end of the plug without modi-

fication of the normal structure of said plug and having openings permitting the covering member to be slipped over the terminals while said terminals are assembled to said body portion, and a plate-like member of insulating material carried by the covering member, and adapted to fit between the said terminals and down into the body of the plug without modification of the normal structure of the plug to separate and insulate the respective terminals and lead-in wires from each other.

80 2. The combination with substantially any conventional terminal plug for electrical connections of the type having a body portion for the lead-in wires and spaced upstanding terminals, a detachable accessory for use therewith comprising a relatively thin plate-like covering member of insulating material adapted to fit over the open end of the plug without modification of the normal structure of said plug and having openings 85 permitting the covering member to be slipped over the terminals while said terminals are assembled to said body portion, and a relatively thin plate-like member of insulating material formed integrally with the covering member and having openings 90

95 permitting the covering member to be slipped over the terminals while said terminals are assembled to said body portion, and a relatively thin plate-like member of insulating material formed integrally with the covering member and having openings 100 permitting the covering member to be slipped over the terminals while said terminals are assembled to said body portion, and a relatively thin plate-like member of insulating material formed integrally with the covering member and having openings 105 permitting the covering member to be slipped over the terminals while said terminals are assembled to said body portion, and a relatively thin plate-like member of insulating material formed integrally with the covering member and having openings 110

115 permitting the covering member to be slipped over the terminals while said terminals are assembled to said body portion, and a relatively thin plate-like member of insulating material formed integrally with the covering member and having openings 120

125 permitting the covering member to be slipped over the terminals while said terminals are assembled to said body portion, and a relatively thin plate-like member of insulating material formed integrally with the covering member and having openings 130

135 permitting the covering member to be slipped over the terminals while said terminals are assembled to said body portion, and a relatively thin plate-like member of insulating material formed integrally with the covering member and having openings 140

145 permitting the covering member to be slipped over the terminals while said terminals are assembled to said body portion, and a relatively thin plate-like member of insulating material formed integrally with the covering member and having openings 150

CHARLES B. CASE, JR. 130
